PHYSICAL EXERCISING APPARATUS

Henry F. Meyers, Spenard, Territory of Alaska
Application August 27, 1956, Serial No. 606,465

8 Claims. (Cl. 128—25)

The invention relates to improvements in physical exercising apparatus, and the invention has reference, more particularly, to apparatus adapted to impart exercising motion to the feet, ankles and legs of the user.

The invention has for an object to provide an exercising apparatus including a power driven oscillatable platform upon which the user stands, and which, in operation, imparts exercising motion to the feet, ankles and legs having effects equivalent to the massaging of these members, whereby to strengthen the muscles and stimulate blood circulation, while at the same time causing foot, ankle and leg joint movements tending to correct any abnormal relative positions of the joint bones.

The invention has for another object to provide a simple, effective and smoothly operating mechanism for imparting oscillatory movement to the platform upon which the user stands.

A further object of the invention is to provide the platform operating mechanism with means for selectively varying the amplitude of oscillation of the platform.

The above and other objects of this invention will become apparent from a reading of the following description of an illustrative embodiment of the invention in connection with the accompanying drawings thereof, in which:

Fig. 1 is a side elevational view of an exercising apparatus according to this invention; Fig. 2 is a horizontal sectional view through the same, taken on line 2—2 in Fig. 1; Fig. 3 is a vertical longitudinal sectional view of the same; and Fig. 4 is a top plan view of the cam plate of the platform operating mechanism of the apparatus.

Referring to the drawings, in which like characters of reference are employed to indicate corresponding parts, the reference character 10 indicates the base of the apparatus. Suitably affixed upon the base 10 is a central bearing hub 11, and a bearing ring 12 concentric to said bearing hub. Supported by said bearing hub 11 and bearing ring 12, for rotation about its vertical axis, is a pedestal drum 13. Said pedestal drum is provided at its bottom end with a worm gear 14, by which it is rotated through power transmission mechanism subsequently herein described. The pedestal drum is preferably of hollow cylindrical formation, the upper end of which is closed by a top plate 15. Pivotedly supported in connection with the upper end of the pedestal drum 13, so as to be carried by the latter for rocking movement relative thereto, is a cam plate 16. The means for pivotally supporting the cam plate 16 in rockable relation to the pedestal drum 13 comprises intermediate, diametrically aligned and spaced apart knuckle connections. Each knuckle connection comprises a bottom knuckle member 17, which is affixed to the top or top plate 15 of the pedestal drum 13, and an upper knuckle member 18, which is affixed to the underside of the cam plate 16 to depend therefrom, and pivotally joined with the bottom knuckle member 17 by a trans-

verse pivot pin 19. As thus supported by the aforesaid knuckle connections, the cam plate 16 can be rocked about the pivoting axis of the knuckle connections, whereby to vary the disposition of its plane from a plane parallel to the horizontal plane of the top of the pedestal drum to an inclined plane relative to the latter of a selected angular degree within a desirable maximum limit, e. g. to a maximum angular plane of twenty-five degrees.

Means is provided to rigidly couple the cam plate 16 to the pedestal drum 13 at a selected angular plane disposition thereof relative to the top plane of the latter. Such means comprises coupling connections which are diametrically aligned at a right angle to the diametric alignment of the knuckle connections 17—18—19. Each said coupling connection comprises an anchoring lug or ear 20 which is suitably positioned and affixed to a side of the pedestal drum 13, so as to project radially and externally therefrom, said anchoring lug or ear having a vertical through opening 21. Slidably adjustable through the opening 21 of the anchoring lug or ear 20 is a perpendicular coupler rod 22, to the upper end of which is pivotally connected a link 23, the opposite end of said link being pivotally connected to a knuckle piece 24 which is affixed to a marginal portion of the cam plate 16, to depend therefrom. Said coupler rod 22 can be locked in a selected adjusted position relative to the anchoring lug or ear 20 by a releasable set screw 25, which is threaded through the wall of the anchoring lug or ear.

Adjustment of the angular pitch of the cam plate 16 is accomplished by releasing the set screws 25, and then moving the coupler rod 22 of one coupler connection upwardly through its supporting anchoring lug or ear 20, whereby to rock the cam plate about its supporting knuckle connections to the pedestal drum, so as to uplift one side of said cam plate, thus lowering the opposite side of said cam plate to correspondingly move the coupler rod 22 of the opposite coupler connection downwardly through its supporting anchoring lug or ear 20. When a desired degree of angular pitch of the cam plate 16 is thus attained, said cam plate can be locked in rigid relation to the pedestal drum 13 so as to rotate with the latter in maintained selected angularly pitched relation thereto. To effect such locked relation, the set screws 25 are tightened home to bind the coupling rods 22 against displacement from their adjusted positions. To indicate and determine various selective degrees of angular pitch of the cam plate 16, one of the coupler rods 22 can be provided with degree indicating graduations for cooperation with the associated anchoring lug or ear 20, as shown in Figs. 1 and 3.

Supported above the cam plate 16 is the oscillatable platform 26 upon which the user of the apparatus can stand subject to the exercising effect thereof. This platform 26 can be of any desired peripheral shape, preferably of generally oblong shape, and its upper surface is preferably faced with anti-slip or frictional means, such e. g. as a rubber mat 26.

The means for supporting the platform 26 comprises a stationary column 27, having its bottom end affixed to the base 10 so as to extend upwardly through the hub bearing 11 and the rotatable pedestal drum 13 in axially aligned relation thereto. To the platform 26 is affixed a centrally disposed supporting arm 28 which projects downwardly from the underside thereof, and through a clearance opening 29 with which the cam plate 16 is provided, so as to be opposed to the upper end of the column 27. The opposed ends of the column 27 and supporting arm 28 are joined together by a universal joint connection 30, whereby to permit os-

cillatory movements of the platform during operation of the exerciser. Mounted on the underside of the platform 26 is a preferably circular bearing plate 31 which is opposed to the cam plate 16. Carried by the cam plate 16, in circumferentially spaced relation around the marginal portions thereof, are a plurality of anti-friction rollers 32, such as ball-bearing type rollers. These rollers are disposed perpendicular to the plane of the cam plate, so as to extend through housing openings 33 with which the cam plate is provided. The rollers 32 are rotatably supported by radial axle shafts 34 which are fixed through the cam plate in extension across the housing openings 33 thereof. As thus mounted, the upper peripheral sides of the rollers project above the top face of the cam plate, so as to thrust against and ride upon the opposed surface of the bearing plate 31 which underlies the platform 26. It will be obvious that the platform 26 does not rotate, but under the thrust of the cam plate 16, when the latter is rotated by rotation of the pedestal drum, will be caused to oscillate with a rocking motion both longitudinally and laterally; the universal joint connection 30 permitting the platform to readily yield to the thrust of the rotated cam plate.

The means for driving the pedestal drum 13 and the cam plate 16 carried thereby comprises a power transmission shaft 35 which is journaled in suitable bearings 36 mounted on the base 10. Said transmission shaft lies in the plane of the worm gear 14 with which the pedestal drum 13 is provided. Fixed on said transmission shaft 35, so as to be rotated thereby, is a worm 37 which meshes with and drives said worm gear of the pedestal drum.

The transmission shaft 35 can be driven from any suitable power source, preferably by an electric motor (not shown) which can be mounted on the base 10. In Figs. 1 and 2, the reference character 38 indicates the armature shaft of the motor, or power shaft of other power source; said shaft 38 being supported, if desired, by a bearing 39 which upstands from the base 10. The power shaft 38 can drive the transmission shaft 35 through an intermediate train of spur gearing 40, which may be of such reduction character as, through the worm 37 and worm gear 14, to rotate the pedestal drum 13 and cam plate 16 at a desired R. P. M. speed. Preferably such speed would not exceed thirty R. P. M.

In the use and operation of the apparatus, the user stands upon the platform 26 with the feet straddling the center point at which the platform is supported by the universal joint connection 30. When thus standing upon the platform, the weight of the user's body is opposed to the movements of the platform, and as the platform is rocked successively in longitudinal and lateral directions, involuntary corresponding movements are imparted to the feet, ankles and legs, whereby the muscles and joints of these members are effectively and beneficially exercised.

Having now described my invention, I claim:

1. Exercising apparatus comprising a base, an upstanding pedestal drum supported on said base, means for rotating said pedestal about its vertical axis, a cam plate, means to pivotally mount said cam plate on the top of said pedestal drum for rocking movement about a transverse axis which intersects the vertical axis of the latter, adjustable means for locking the cam plate to the pedestal drum at an inclined plane of selected angular degree relative to the plane of the top of said pedestal drum, said adjustable means comprising a pair of adjustable coupling connections intermediate the pedestal drum and cam plate and diametrically aligned at a right angle to the pivotal axis of the latter, each coupling connection including means to lock the same to the pedestal drum in a selected adjusted condition, a non-rotatable platform adapted to be engaged and oscillated

by rotary movement of said pedestal drum and cam plate, a platform supporting column upstanding from said base to extend axially through said pedestal drum and cam plate, and a universal joint connection coupling said platform to said supporting column.

2. Exercising apparatus comprising a base, an upstanding pedestal drum supported on said base, means for rotating said pedestal drum about its vertical axis, a cam plate, means to pivotally mount said cam plate on the top of said pedestal drum for rocking movement about a transverse axis which intersects the vertical axis of the latter, adjustable means for locking the cam plate to the pedestal drum at an inclined plane of selected angular degree relative to the plane of the top of said pedestal drum, said adjustable means comprising a pair of adjustable coupling connections intermediate the pedestal drum and cam plate and diametrically aligned at a right angle to the pivotal axis of the latter, each coupling connection comprising an anchoring lug radially projecting from a side of the pedestal drum, a perpendicular coupler rod slidably movable through said anchoring lug, a link pivotally connected by its lower end to said coupler rod, means to pivotally connect said link by its upper end to the cam plate, and a set screw threaded through the wall of said anchoring lug to releasably secure the coupler rod in a selected adjusted position, a non-rotatable platform adapted to be engaged and oscillated by rotary movement of said pedestal drum and cam plate, a platform supporting column upstanding from said base to extend axially through said pedestal drum and cam plate, and a universal joint connection coupling said platform to said supporting column.

3. Exercising apparatus according to claim 2, wherein at least one of the coupler rods is provided with cam plate angle degree determining graduations for cooperation with its supporting anchoring lug.

4. Exercising apparatus according to claim 2, wherein the cam plate is provided with a plurality of circumferentially spaced anti-friction rollers, and the underside of the platform is provided with a bearing plate against which said rollers thrust and ride.

5. Exercising apparatus comprising a base, an upstanding pedestal drum supported on said base, said pedestal drum including a worm gear for rotating the same about its vertical axis, a power driven transmission shaft, bearing means on said base by which said shaft is supported, a worm on said shaft to engage and drive the pedestal drum worm gear, a cam plate, means to pivotally mount said cam plate on the top of said pedestal drum for rocking movement about a transverse axis which intersects the vertical axis of the latter, adjustable means for locking the cam plate to the pedestal drum at an inclined plane of selected angular degree relative to the plane of the top of said pedestal drum, said latter means comprising a pair of adjustable coupling connections intermediate the pedestal drum and cam plate and diametrically aligned at a right angle to the pivotal axis of the latter, a non-rotatable platform adapted to be engaged and oscillated by rotary movement of the pedestal drum and cam plate, a platform supporting column upstanding from said base to extend axially through said pedestal drum and cam plate, and a universal joint connection coupling said platform to said supporting column.

6. Exercising apparatus according to claim 5, wherein the cam plate is provided with a plurality of circumferentially spaced anti-friction rollers to thrust and ride against the platform.

7. Exercising apparatus according to claim 5, wherein the coupling connections intermediate the pedestal drum and cam plate each comprise an anchoring lug radially projecting from a side of the pedestal drum, a perpendicular rod slidably movable through said anchoring lug, a link pivotally connected by its lower end to said coupler rod, means to pivotally connect said link by its upper

end to the cam plate, a set screw threaded through the wall of said anchoring lug to releasably secure the coupler rod in a selected adjusted position.

8. Exercising apparatus according to claim 7, wherein the cam plate is provided with a plurality of circumferentially spaced anti-friction rollers, and the underside of

the platform is provided with a bearing plate against which said rollers thrust and ride.
